(57) **CLAIM**

The ornamental design for display screen or portion thereof with animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with animated graphical user interface;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The appearance of the animated graphical user interface transitions sequentially between the image shown. The process or period in which one image transitions to another forms no part of the claimed design.

The broken lines showing a display screen or portion thereof and elements of the graphical user interface illustrate portions of the article, and form no part of the claimed design.
